CLAIM

The ornamental design for a diving mask, as shown and described.

DESCRIPTION

FIG. 1 is a front perspective view of a diving mask, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 2. The broken lines in the drawings illustrate the portions of the diving mask, which form no part of the claimed design. The dash-dot-dash broken lines depict the bounds of the enlarged portions of the diving mask and form no part of the claimed design.
